REVERSIBLE IMPACT DRIVING SCREW
DRIVER AND FUNCTIONAL ELEMENTS
THEREOF

James F. Spielman, Torrington, Conn.

Application May 2, 1952, Serial No. 285,743

4 Claims. (Cl. 81—52.3)

1

The invention brings forth a new screwdriver which transmits an impact of an object upon its handle to a rotative impulse of its working blade. The screwdriver may be adjusted to transmit an impact of an object upon its handle to a rotative impulse of its working blade in either direction of rotation. Thus a reversible impact driving screwdriver is defined.

The invention is additionally adjustable for use as an ordinary screwdriver.

The invention brings to light a new screwdriver with which fastening screws may be tightened securely and with which tight screws may be easily loosened. In the following description, referring to the accompanying drawing, an unusual method of operation for accomplishing these functions will become apparent.

An ordinary screwdriver comprises merely a handle, or body, and a working blade. Numerous types of fastening screw heads and screwdriver working blades exist. Therefore, a "screw" will herein be interpreted to mean any screwing fastener having any type head for engagement with a screwdriver working blade; a "working blade" will herein be interpreted to mean any member projecting from the body of a screwdriver embodying the invention for the purpose of engaging a screwing fastener.

The primary object of the invention is to provide a new screwdriver which will transmit an impact of an object upon its handle to a rotative impulse of its working blade, which is adjustable for operation in either direction of rotation, and which is further adjustable for use as an ordinary screwdriver.

A further object of the invention is to provide a design of the invention involving a minimum of parts which operate with maximum efficiency.

The fulfillment of the foregoing objects becomes apparent in the following description of the accompanying drawing, in which Fig. 1 is a vertical cross-sectional view of the invention; Fig. 2 is a vertical cut-away view of the invention orthographically projected from Fig. 1; Fig. 3 is an operational view comparable with Fig. 2; and Fig. 4 is a cross-sectional view taken along line 4—4 of Fig. 2.

A handle or body 5 has a cylindrical interior opening at one end thereof, wherein a tubular adjusting sleeve 6 is rotatably carried. The adjusting sleeve 6 may embody a finger flange 7 on a portion projecting from the body 5 for manual adjustment by the fingers. The adjusting sleeve 6, in the illustrated form of the invention, contains a pair of diametrically disposed, peripherally extending

2

adjustment slots 8 and 9 through the wall thereof; and the adjustment slots 8 and 9 each comprise three setting notches in the outward-facing longitudinal sides thereof.

5 An impact sleeve 10 is shown press-fitted into the adjusting sleeve 6, thereby being operatively non-slidable and non-rotatable in respect to the adjusting sleeve 6. The impact sleeve 10 diminishes symmetrically from two diametrically opposite points thereon to the outward-facing end thereof, whereby to provide two diametrically opposite guide points 11 and 12, and whereby to provide a plan (see Fig. 2) of four angular inclines (13 and an unreferenced diametrical cooperating opposite) and (14 and an unreferenced diametrical cooperating opposite). Thus, when Fig. 2 especially is observed, the screwdriver is seen to be symmetrical about a vertical center line.

10 A centering sleeve 15 corresponds with the impact sleeve 10 in that it contains four inward-facing angular inclines (16 and an unreferenced diametrical cooperating opposite) and (17 and an unreferenced diametrical cooperating opposite), loosely meshing with the impact sleeve 10. Space for a degree of rotation of the impact sleeve 10 in either direction relative to the centering sleeve 15 is provided.

15 A pair of aligned retaining pins 21 and 22 pass from the body 5 diametrically through the adjusting sleeve 6 into the adjustment slots 8 and 9, and fix the body 5 with the centering sleeve 15. The adjusting sleeve 6 is rotatably mounted relative to the centering sleeve 15.

20 A drive piston 18 is slidably and rotatably mounted in the centering sleeve 15 and the impact sleeve 10. A type of screwdriver working blade 23 is fixed in and projects outwardly from the radial center of the drive piston 18.

25 A drive pin 19 passes diametrically through the drive piston 18 and engages a pair of drive pin receiving normal notches 20 and 25 at the nearest inward-facing end of the centering sleeve 15.

30 A compression spring 24 is compressed between an abutment at the inward-facing end of the impact sleeve 10 and drive piston 18. The spring 24 urges the drive piston 18 outward and urges the adjusting sleeve 6 inward, engaging the retaining pins 21 and 22 against the setting notches in the adjustment slots 8 and 9.

35 The plan of operation is readily seen when Figs. 2 and 3 are observed. As seen in Figs. 1 and 2, the invention may be applied as an ordinary screwdriver, in that the working blade 23 may be engaged with a type of screw (not shown) and rotated manually by the body 5 to turn the screw.

The drive pin 19 is retained in the normal notches 20 and 25 by the guide points 11 and 12, mechanically fixing the working blade 23 with the body 5.

Examination of Fig. 3, compared with Fig. 2, reveals the plan of impact operation and adjustment. The adjusting sleeve 6 may be rotated toward the figure "L" on the body (Fig. 2) until the ends of the adjustment slots 8 and 9 engage the retaining pins 21 and 22 (Fig. 3). This rotation of the adjusting sleeve 6 is accompanied by a negligible outward sliding action as the retaining pins 21 and 22 pass from the center setting notches to the end setting notches (Fig. 3). The adjustment toward "L" removes the guide points 11 and 12 from alignment with the drive pin 19. A user may now engage the working blade 23 with a type of screw (not shown), grip the body 5 tightly and strike a blow upon the top (as shown) of the body 5 with the palm of his hand or with some inanimate object. The impact of the blow engages the drive pin 19 with the angular inclines (16 and cooperating opposite) on the centering sleeve 15 and guide the drive pin 19 to the normal notches 20 and 25. A cycle of impact operation is completed.

It is apparent that an adjustment toward "T" (Fig. 2) adjusts the invention for a tightening impulse when operated. This is readily seen when the drawing is held before a mirror.

In the illustrated construction of the invention, the impact force of the drive pin 19 against the angular inclines of the impact sleeve 16 is carried to the body 5 by abutment of the inward end of the adjusting sleeve 6 with the end of the cylindrical interior of the body 5, requiring the retaining pins 21 and 22 to bear only the rotative load.

The invention in substance is seen in a plan of corresponding cooperating angular inclines, involving the four angular inclines on the impact sleeve 16 being adjustable relative to the drive pin 19 and to the four angular inclines on the centering sleeve 15, to determine the direction of operational rotative impulse. A basic or "half" plan of angular inclines is apparent in Fig. 2. A practical method for adjusting the cooperating angular inclines has been disclosed. However, aside from the basic plan of cooperating angular inclines and drive pin, other arrangements for adjusting the impact sleeve 16 relative to the centering sleeve 15 and drive pin 19 may be employed. Examination of the drawing, for example, reveals that the invention will function if any number of retaining pins as a unit operate relative to any number of adjustment slots as a unit when one or more of the adjustment slots contains a unit of setting notches.

Any fastening means outside of the invention may be used for fixing a screw driver working blade of any type in the drive piston 18.

Having disclosed a practical design of my invention, and being aware of possible modifications of the elements thereof, I set forth the following claims:

1. In a reversible impact driving screwdriver, a body having a cylindrical interior opening therefrom, an impact sleeve carried concentrically within said cylindrical interior of said body, said

impact sleeve diminishing symmetrically from two diametrically opposite points thereon to the outward-facing end thereof whereby to comprise four angular inclines and a pair of diametrically opposite guide points, said impact sleeve being manually rotatively adjustable in said body to a limit in either direction and to a normal intermediate point, a centering sleeve aligned concentrically with and outwardly from said impact sleeve, said centering sleeve being fixed within said body, said centering sleeve diminishing symmetrically from two diametrically opposite points thereon to the inward-facing end thereof whereby to comprise four angular inclines, a drive piston carried concentrically in said centering sleeve and said impact sleeve, said drive piston being slidable and rotatable relative to said centering sleeve and said impact sleeve, said drive piston having means thereon for fixing a screwdriver working blade thereto, a compression spring urging said drive piston outwardly from said centering sleeve and said impact sleeve, and a drive pin means carried diametrically through said drive piston and normally engaging a space between the farthest outward-facing end of said impact sleeve and the nearest inward-facing end of said centering sleeve, whereby said impact sleeve and said centering sleeve function with said drive pin in a plan of cooperating angular inclines.

2. In a reversible impact driving screwdriver, a body having a cylindrical interior opening therefrom, a tubular adjusting sleeve carried concentrically in and rotatable in said cylindrical interior of said body, said adjusting sleeve having a portion thereof projecting from said body for rotative adjustment by hand, said adjusting sleeve comprising a unit of peripherally extending adjustment slots through the wall thereof, an impact sleeve fixed in the inward-facing end of said adjusting sleeve whereby to rotate therewith, said impact sleeve diminishing symmetrically from two diametrically opposite points thereon to the outward-facing end thereof whereby to comprise four angular inclines and a pair of oppositely disposed guide points, a centering sleeve concentrically aligned with said impact sleeve and carried in the outward-facing end of said adjusting sleeve, said centering sleeve being rotatably mounted in relation to said adjusting sleeve, said centering sleeve diminishing symmetrically from two diametrically opposite points thereon to the inward-facing end thereof whereby to comprise four angular inclines corresponding with the said angular inclines on the outward-facing end of said impact sleeve, a retaining pin unit passing from said body through said adjusting sleeve into said adjustment slot unit through the wall of said adjusting sleeve and engaging said centering sleeve whereby to non-rotatably fix said centering sleeve within said body, a drive piston concentrically carried in said centering sleeve and said impact sleeve, said drive piston being slidable and rotatable relative to said centering sleeve and said impact sleeve, means for fixing an externally projecting screwdriver working blade element in the said drive piston, a drive pin projecting diametrically through said drive piston and normally engaging a gap between the farthest outward-facing end of said impact sleeve and the nearest inward-facing end of said centering sleeve, a compression spring urging said drive piston outwardly from said centering sleeve and said impact sleeve, and means for manual rotative positioning of said adjusting sleeve to an extreme in either direction and to an intermediate point at which said

oppositely disposed guide points on said impact sleeve align with said drive pin projecting diametrically through said drive piston.

3. In a reversible impact driving screwdriver, a body having a cylindrical interior opening therefrom, a tubular adjusting sleeve carried concentrically in and rotatable in said cylindrical interior of said body, said adjusting sleeve having a portion thereof projecting from said body for rotative adjustment by hand, said adjusting sleeve comprising a unit of peripherally extending adjustment slots through the wall thereof, said unit of adjustment slots containing a unit of three evenly spaced setting notches on the outward-facing side thereof, an impact sleeve fixed in the inward-facing end of said adjusting sleeve whereby to rotate therewith, said impact sleeve diminishing symmetrically from two diametrically opposite points thereon to the outward-facing end thereof whereby to comprise four angular inclines and a pair of diametrically disposed guide points, a centering sleeve concentrically aligned with said impact sleeve and carried in the outward-facing end of said adjusting sleeve, said centering sleeve being rotatably mounted relative to said adjusting sleeve, said centering sleeve diminishing symmetrically from two diametrically opposite points thereon to the inward-facing end thereof whereby to comprise four angular inclines corresponding with the said angular inclines on the outward-facing end of said impact sleeve, a retaining pin unit passing from said body through said adjusting sleeve into said adjustment slot unit through the wall of said adjusting sleeve and engaging said centering sleeve whereby to fix said centering sleeve within said body, a drive piston concentrically carried in said centering sleeve and said impact sleeve, said drive piston being slidable and rotatable relative to said centering sleeve and said impact sleeve, means on said drive piston for fixing an externally projecting screwdriver working blade element thereto, a drive pin projecting diametrically through said drive piston and normally engaging a gap between the farthest outward-facing end of said impact sleeve and the nearest inward-facing end of said centering sleeve, and a compression spring compressed between said drive piston and said adjusting sleeve by a base within the inward-facing end of said adjusting sleeve, said compression spring urging said drive piston outwardly and urging said adjusting sleeve inwardly to engage said setting notch unit with said retaining pin unit, whereby a rotative adjustment

of said adjusting sleeve engaging the intermediate notch of said setting notch unit with said retaining pin unit aligns said diametrically disposed guide points on said impact sleeve with said drive pin projecting diametrically through said drive piston.

4. A screwdriver, said screwdriver being adjustable to transmit an impact upon the body thereof to a rotative impulse of the working blade thereof in either direction of rotation, said screwdriver embodying a combination of elements in the body thereof for operation and adjustment, said combination of elements including: a centering sleeve element comprising inward-facing angular inclines fixed within an open first end of said body, an impact sleeve element concentrically aligned with said centering sleeve element toward a closed second end of said body, said impact sleeve element comprising outward-facing angular inclines, said impact sleeve element being manually rotatively adjustable relative to said centering sleeve element to a limited degree and to an intermediate point at which the farthest outward-facing end of said impact sleeve element aligns with the nearest inward-facing end of said centering sleeve element, a drive piston element carried slidably and rotatably within said centering sleeve element and said impact sleeve element, said drive piston element being adapted to contain a screwdriver working blade projecting from said first end of said impact sleeve element aligns with the diametrically in said drive piston element and normally engaging a space between the farthest outward-facing end of said impact sleeve element and the nearest inward-facing end of said centering sleeve element, whereby said centering sleeve element and said impact sleeve element operate with said drive pin element in a plan of cooperating angular inclines.
